UNITED STATES PATENT OFFICE.

MICHAEL J. FOGARTY, OF BROOKLYN, NEW YORK.

DEVICE FOR FEEDING AND COMPRESSING GRANULAR MATERIALS.

1,164,276.

Specification of Letters Patent. Patented Dec. 14, 1915.

Application filed January 26, 1915. Serial No. 4,476.

To all whom it may concern:

Be it known that I, MICHAEL J. FOGARTY, a citizen of the United States, and resident of Brooklyn, in the county of Kings and State of New York, have invented certain new and useful Improvements in Devices for Feeding and Compressing Granular Materials, of which the following is a specification.

10 The invention relates to improvements in devices for feeding and compressing granular materials of various kinds, the same being particularly designed for compacting materials for filling packages; and the object of the invention is to provide a device having a more positive feeding and compressing action, and also includes certain details of construction hereinafter set forth.

In describing the invention in detail reference is had to the accompanying drawings, forming part of this specification, and wherein like characters of reference are used to designate corresponding parts throughout the several views, and in which:

25 Figure 1 is a side elevation, shown partially in section, of the device embodied in the present invention; and Fig. 2 is an end elevation of the same, the casing thereof being shown partially in section taken along 30 the broken line $\alpha-\alpha$, Fig. 1.

In the drawings, numeral 1 designates a casing, having at its lower end the supporting feet 2, and at its upper end a receiving-hopper 3 for the material operated upon. A bearing 4 is formed on one side wall of the casing, and the bottom wall 5 of the latter is semicircular in form and disposed concentrically with the axis of said bearing. Within the casing is mounted a worm 6, having an integral journal-end 7, mounted for rotation within the bearing 4, and driven by the exterior pulley 8, fixed to said journal-end. Above the worm the casing is provided with bearings 9, in which is rotatably mounted a shaft 10, laterally positioned by the exterior collars 11, and upon the shaft is fixed a worm-wheel 12, engaged for rotary movement by the worm 6. Fixed upon the shaft, within the casing and on opposite sides of the worm-wheel, are pressure-wheels 13, the peripheries of which conform with and lie closely adjacent the circumference of the worm 6. Projecting ledges 14 are provided on the peripheral surfaces of the pressure-wheels, and are spirally arranged thereon with respect to the movement of the wheels

for the advancement of the material. Toward its upper end the receiving-hopper 3 is outwardly flared to increase its storage capacity, and in connection therewith the 60 casing is provided with a circular projecting portion 15, arranged to incase the upwardly moving part of the worm-wheel and the pressure-wheels and control in a measure the flow of the material. For delivering 65 the compressed material the casing is provided with a discharge opening or spout 16, having a cylindrical portion encircling the delivery end of the worm and a tapered outlet portion of gradually reduced internal 70 area.

In the operation of the device, the material fed into the receiving-hopper 3 is urged downwardly by the movement of the projecting teeth of the worm-wheel 12 and the 75 ledges formed on the pressure-wheels 13, which movement tends to prevent the choking action of the material within the hopper and serves also to feed the same between the spiral threads of the worm 6. By the 80 rotation of the worm in the direction indicated by the arrow, the material is uniformly advanced to the point of engagement with the worm-wheel, from which point the engaging teeth of the latter serve to forwardly force the material in a substantially 85 positive manner along the advancing spiral groove of the worm to the discharge-spout 16, the tapering wall of the latter offering by its reduced internal area a resistance to the 90 flow of the material which acts to compress the latter. For preventing lateral displacement from the worm of the material under pressure, the peripheral surfaces of the pressure-wheels 13, as heretofore described, are 95 shaped to conform with the circumference of the worm, and the spiral arrangement of the ledges on said wheels serves to direct the material both forwardly, and inwardly toward the worm, for increasing its pressure 100 and reducing its friction against the side walls of the casing. By varying the internal diameter of the discharge spout, a corresponding variation in the pressure of the discharged material may be obtained for its 105 delivery by any approved means into suitable containers.

What I claim as my invention and desire to secure by Letters Patent is:

1. In a feeding and compressing device, a 110 casing having a supply opening for the material, a rotatable worm in said casing, a

worm-wheel rotatably engaged by said worm, means co-acting with said worm and worm-wheel, for confining the material against lateral displacement from said 5 worm, and a discharge-opening in said casing communicating with said worm.

2. In a feeding and compressing device, a casing having a supply opening for the material, a worm in said casing rotatably supported at one end, a worm-wheel rotatable in said casing and engaged by said worm, pressure-wheels mounted on opposite sides of said worm-wheel and rotatable therewith and having the peripheries thereof conforming 10 with the circumference of said worm, and a discharge opening for said casing having a cylindrical portion encircling the delivery end of said worm and a tapered outlet portion of gradually reduced internal 15 area.

3. In a feeding and compressing device, a casing having a supply opening for the material, a worm in said casing rotatably supported at one end, a worm-wheel rotatable 20 in said casing and engaged by said worm, pressure-wheels mounted on opposite sides of said worm-wheel and rotatable therewith and having the peripheries thereof conforming 25 with the circumference of said worm, spirally formed ledges projecting from the peripheral surfaces of said pressure-wheels and disposed to advance the material toward 30 said worm, and a discharge opening for said casing having a cylindrical portion encircling 35 the delivery end of said worm and a tapered outlet portion of gradually reduced internal area.

4. In a feeding and compressing device, a casing provided with a bearing, a semicircular bottom wall for said casing concentric 40 with the axis of said bearing, a worm dis-

posed within said casing and having an integral journal-end mounted in said bearing and provided with rotative means, a supply-hopper at the upper end of said casing and 45 arranged to deliver the material by gravity to said worm, a worm-wheel mounted for rotation in said hopper and engaged by said worm, pressure-wheels mounted at opposite sides of said worm-wheel and rotatable 50 therewith and having the periphery thereof conforming with the circumference of the worm, feed-projections formed on the peripheral surface of said pressure-wheels, and a discharge-opening for said casing having 55 a cylindrical portion encircling the delivery end of said worm and a tapered outlet portion of gradually reduced internal area.

5. In combination with a feeding device including a rotatable worm, of opposing pressure-wheels rotatably mounted above 60 said worm and having peripheral surfaces conforming with the circumference thereof and arranged to direct the material thereto.

6. In combination with a feeding and compressing device including a worm and worm-wheel in rotatable engagement, of pressure-wheels disposed on opposite sides of said worm-wheel and rotatable therewith and having peripheral surfaces conforming 70 with the circumference of said worm, and spirally-formed ledges projecting from the peripheral surfaces of said pressure-wheels and disposed to advance the material toward 75 said worm.

Signed at Brooklyn in the county of Kings and State of New York this 21st day of Jan. A. D. 1915.
